United States Patent Office

Des. 211,819

Patented July 30, 1968

211,819

KITCHEN SPOON OR SIMILAR ARTICLE

Dorothy J. Connor, Northlake, and Thomas W. Heermans, Deerfield, Ill., assignors to American Home Products Corporation, New York, N.Y., a corporation of Delaware

Filed Nov. 22, 1967, Ser. No. 9,512

Term of patent 14 years

(Cl. D44—29)

FIG. 1 is a top plan view of a kitchen spoon or similar article showing our new design.

FIG. 2 is a side elevational view thereof.

FIG. 3 is an enlarged section taken along line 3-3 of FIG. 1.

The dominant feature of our new design resides in the portion shown in full lines.

We claim:

The ornamental design for a kitchen spoon or similar article, substantially as shown and described.
